(57) **CLAIM**

The ornamental design for replacement caps for pen-injector devices, substantially as shown and described.

DESCRIPTION

FIG. 1 is a perspective view of a replacement cap in accordance with the design in the environment of having it attached to a pen-injector device.

FIG. 2 is a perspective view thereof;

FIG. 3 is another perspective view thereof;

FIG. 4 is a right-side elevation view thereof;

FIG. 5 is a left-side elevation view thereof;

FIG. 6 is a front elevation view thereof;

FIG. 7 is a rear elevation view thereof;

FIG. 8 is a top plan view thereof; and,

FIG. 9 is a bottom plan view thereof.

The broken lines represent the bounds of the claimed design or are otherwise directed to environment or for illustrative purposes only. The broken lines form no part of the claimed design.

1 Claim, 8 Drawing Sheets
